SELF-OILING DIE STOCK

Ernest S. Gremillion, Bunkie, La.

Application October 15, 1937, Serial No. 169,289

1 Claim. (Cl. 10—126)

This invention relates to die stocks and more particularly to a die stock provided with means whereby oil or any other suitable lubricant may be applied to the die.

5 In accordance with the present invention a die stock is provided in such a manner that one handle of the die stock serves as a reservoir for the lubricant, while the head carrying the dies is provided with passages therethrough so that the oil or other lubricant will discharge upon the 10 dies and upon the work being cut by the die.

The invention together with its objects and advantages will be best understood from a study of the following description taken in connection 15 with the accompanying drawings wherein:—

Figure 1 is a plan view of a die stock embodying the features of the present invention.

Figure 2 is a side elevational view of the die stock.

20 Figure 3 is an enlarged fragmentary detail sectional view through the die stock at the die-holder end thereof.

Figure 4 is a fragmentary sectional view on a vertical plane through the die-holder end of the 25 die stock, and

Figure 5 is a longitudinal sectional view through the handle of the die stock at the end thereof remote from the die holder.

Referring to the drawings more in detail it will 30 be seen that 5 indicates generally the die holder, the same being substantially of conventional construction, embodying as it does a frame 6 provided with a stem or socket 7, and arranged within the frame is a head 8 carrying the dies 9 of the kind used for cutting thread, and for similar 35 purposes.

The handle for the die stock is indicated by the reference numeral 10 and in the present instance is shown as consisting of an elongated 40 tubular member that at one end threads into the socket 7 as at 11. At said end the handle member 10 is provided with an integral plug 12 having a passage 13 therethrough controlled by a spring-seated ball check valve 14.

45 For the outer end of the handle 10 there is provided a cap 15 which is apertured to accommodate a stem or rod 16 of a plunger or piston 17 that has a working fit within the handle 10.

Inwardly from the cap-equipped end thereof 50 handle 10 is provided with a partition wall 18 that is apertured to accommodate the stem 16, and disposed about the stem 16, and bearing at one end on the partition wall 18 is a coil spring 19. The other end of the spring 19 bears against 55 a transverse pin 20 carried by the stem 16 and

spring 19 normally acts on the stem to project the handle-equipped end 21 of the stem outwardly as will be clear from a study of Figure 5.

Also inwardly from the region of the wall 18 handle 10 is provided with a filling neck 22 for 5 which a closure plug 23 is provided. It is obvious that the oil or lubricant is introduced into the handle 10 through the neck 22.

So as to permit the piston 17 to move away from the head 8 or towards the right in Figure 3, 10 the piston or plunger 17 is provided with an oil passage 24 therethrough and for the passage 24 there is provided at the leading side of the piston 17 a suitable flexible flap valve 25.

Further in accordance with the present invention, the head 8 carrying the dies 9 is provided with a circular series of relatively spaced radial oil ports 26 which during the threading operation successively pass into alignment with passage 13 in the handle 10 to permit oil discharging from 20 the handle to pass therethrough for lubricating the dies 9 and the work during the threading operation.

From the above it will be apparent that in practical operation when rod 16 is pushed inwardly of the handle 10 plunger 17 will act to 25 force the oil in advance of said plunger through the passage 13, unseating the valve 14 and through the successive ports or passages 26. When the end 21 is pulled outwardly with respect 30 to the handle 10, the resistance of the lubricant within the handle to the movement of the piston 17 is reduced due to the fact that valve 25 will flex to an open position thus leaving a through or uninterrupted passage 24 for the oil through 35 the piston 17.

It is thought that a clear understanding of the construction, utility and advantages of a die stock embodying the features of the present invention will be had without a more detailed 40 description.

Having thus described the invention what is claimed as new is:—

In combination with an annular die holder frame having a die supporting head releasably 45 mounted therein for rotation and provided with a series of radially arranged lubricating ports to carry lubricant to the dies of the head and work engaged by the dies, an internally screw threaded socket formed on the frame, a handle having a 50 plug-like end externally screw threaded and threaded in the socket and provided with a lubricant reservoir extending from the plug-like end through the free end of the handle, a cap detachably secured on the free end of the handle 55

- 5 for closing one end of the reservoir, said plug-like end of the handle having a lubricant passage leading from said reservoir and adapted to communicate with the ports of the head during rotation of the latter relative to the frame, a check valve in said passage to prevent lubricant and cuttings from the head from passing into the reservoir by way of the passage, a stem slideable in the reservoir and cap and including a finger piece 10 arranged outwardly of the reservoir, a piston having a port there-through secured on the stem and having a frictional fit with the walls of the reservoir, a flap valve for the port of said piston, a partition in said reservoir adjacent the cap and 15 having said stem slideable there-through, a pin secured on the stem between said partition and

cap for limiting the sliding movement of the piston, a coil spring on said stem and bearing against the partition and pin and acting to urge the piston towards the partition for charging the portion of the reservoir between said piston and the plug-shaped end of the handle with lubricant obtained from the reservoir between said piston and the partition, and said handle remote from said die holder being provided with a filling neck extending at an angle of about 45° from said handle 10 towards the outer end of the handle, so that lubricant may be easily poured therein when said handle is positioned in an upward direction from the work engaged by the die holder, and a closure plug for said filling neck.

ERNEST S. GREMILLION.
